UNITED STATES PATENT OFFICE.

CHARLES STANLEY JACOB, OF ELIZABETH, NEW JERSEY.

SIGNALING DEVICE.

1,282,585.

Specification of Letters Patent. Patented Oct. 22, 1918.

Application filed May 16, 1918. Serial No. 234,922.

To all whom it may concern:

Be it known that I, CHARLES STANLEY JACOB, a citizen of the United States, residing at Elizabeth, in the county of Union, 5 State of New Jersey, have invented certain new and useful Improvements in Signaling Devices, of which the following is a specification, reference being had therein to the accompanying drawings, which form a part 10 thereof.

My invention relates to signaling devices and more particularly to a device adapted for use in field, marine and aerial work.

Heretofore for signaling by hand, it has 15 been almost the universal practice to employ flags and indicate by means of these flags the different letters of the alphabet by a system of "wig-wagging". These flags are affected by the air currents, however, so 20 that under some conditions, particularly if the signaler be upon a vehicle such as an aeroplane, traveling at high speed, it is difficult to read the signal. This condition is exaggerated by the fraying of the flags and 25 their change of color, due to exposure. The fluttering of the flag in the wind, or its furling upon the staff, makes it difficult under all conditions to send clear-cut signals.

With these conditions in mind, the object 30 of my invention is to provide a signaling device which may at all times be exposed to the full extent in a plane at right angles to the line of vision of the operator at the receiving station, thus permitting absolute 35 certainty in the sending and receiving of messages. By avoiding partial obscuration of the device such as follows from the fluttering, or partial furling, of a bunting flag, the range of signaling may be much in- 40 creased, it being possible, topographical conditions permitting, to increase the range of visibility of the signal from one to two miles with the naked eye, and to a considerably greater distance if the operator at the re- 45 ceiving station uses field glasses, binoculars, or a telescope, determined largely by the range of the glasses, etc.

A signaling device made in accordance 50 with my invention, while being so constructed as to always be extended to the full extent while in use in signaling, is also capable of being collapsed in a manner to be readily packed in the equipment of the user thereof.

The invention consists primarily in a signaling device, embodying therein a sequence 55 of rigid panels, means holding said panels

with relation to each other, whereby the signal in its entirety may be collapsed, and means whereby said panels are held against movement when the device is extended, said 60 panels being so colored as to present a well defined design thereon when extended, and in such other novel features of construction and combination of parts as are hereinafter set forth and described, and more particularly pointed out in the claims hereto appended.

Referring to the drawings:

Figure 1 is a front view of a signaling device embodying my invention; 70

Fig. 2 is a vertical section on the line 2—2 of Fig. 1;

Fig. 3 is a front view of the device folded; and

Fig. 4 is a top view of the device folded. 75

Like letters refer to like parts throughout the several views.

In the embodiment of my invention shown in the drawings, I employ a sequence of panels or strips *a*, of aluminium, wood, or other light rigid material, the edges of adjoining panels being hinged together as at *b*, so as to permit them to be folded upon each other in a manner to collapse the signal in its entirety and bring it within sufficiently small compass to facilitate its being packed in the equipment of the user. 85

The end panels or strips *a* have along the free edge thereof, a flange forming a pocket *c*—*d* extending longitudinally of said 90 panel or strip, adapted to receive the stay strips *e* and *f* when the device is folded. Said strips, when the device is opened, serve to hold it in the distended position with the desired degree of rigidity, and are pivotally 95 connected to opposite ends of the flanges *c*—*d* respectively.

The stay strips *e* and *f* are provided with sockets *e'* and *f'* adjacent one edge thereof, adapted to receive tongues *a'* carried by 100 some of the panels or strips *a*, thus affording a support for said panels intermediate the edges of the device.

The panels or strips *a* are arranged in two groups, disposed upon opposite sides of a 105 central staff *g*, toward which the panels of each group fold when the device is collapsed.

One end of the staff *g* is provided with an operating handle *g'*, thus securing a balanced condition in the signal, which facilitates its use. 110

The staff *g* is also provided with sockets *h* and *i*, adjacent the top of said staff and adjacent the handle *g'*, said sockets being adapted to receive the stay strips *e* and *f*, 5 and hold them in position when the device is distended. Said sockets *h* and *i* are provided respectively with set screws *h'* and *i'*, thus avoiding accidental displacement of said strips. Other means for securing these 10 strips in position may be employed if desired, although I have found the structure described desirable in that it maintains this securing means in a position which will not interfere with the collapsing or extending of 15 the signal.

The end panels or strips *a* each have pivotally connected therewith, a hook *j*—*k*, said hooks being of a length to project across the ends of all of the panels or strips when the 20 device is folded, and being so formed as to engage the other end panel and thus hold the device in this collapsed position. Adjacent each hook, I provide an opening through the panel through which, when the device is distended, said hook may pass so as to cause the hook to lay flat against its panel.

The various panels are so colored that when the device is distended, it will present any desired design. In the accompanying 30 drawings, I have shown a white field with a red square at the center thereof, but it is apparent that this coloring may be varied according to the requirements of the regulations governing signaling devices of the semaphore type.

The operation of the signaling device made in accordance with my invention is substantially as follows:—

When the device is not in use, the panels 40 or strips *a* are folded one against the other toward the staff *g* as shown in Figs. 3 and 4, the hook *j* extending across one end of the folded panels or strips and the hook *k* extending across the other end thereof in a 45 manner to prevent the accidental opening of the signal. When so folded, the various panels or strips *a* are disposed in their entirety upon one side of said staff, the grouping of these panels or strips in the manner 50 described bringing the handle *g'* centrally of the collapsed structure. When the device is thus folded, the stay strips *e* and *f* seat within the pockets formed by the flanges *c* and *d*, being held in this position by the ends 55 of said hooks.

In folding, the various panels fold away from the sockets *h* and *i*.

When it is desired to use the signal, the hooks *j*—*k* are swung upon their pivots, and 60 the various panels *a* are drawn outwardly from the staff *g* to the full extent, the stay strips *e* and *f* being successively swung about their pivots, one upwardly and the other downwardly, until the free ends thereof 65 enter the pockets at the opposite edge of the

extended structure. As said stay strips enter said pockets, they will exert a lateral stress upon all of the panels or strips *a* and thus draw said panels or strips out to the full extent, and provide a flat rigid structure surrounded by a frame composed of the material of said pockets and said stay strips. As the 70 said stay strips *e* and *f* come to place, they will enter the sockets *h* and *i* respectively, thus not only serving to retain said stay strips in position, but also preventing a rotative movement of the signal in its entirety upon the staff *g*. The sockets *e'* and *f'* upon said stay strips, will also be brought into 75 operative engagement with the tongues *a'*. 80

When the device is extended, the hooks *j* and *k* are swung upon their pivots until they enter the openings in the panels to which 85 said hooks are pivoted, thus keeping said hooks within the plane of the structure and preventing the breakage thereof.

In use, a signaling device made in accordance with my invention, is held at right angles to the line of vision of the observer at the receiving station, and is moved in this 90 plane in accordance with the particular signaling code used. The device being entirely rigid, the full surface thereof is always exposed to the observer, and may, therefore, 95 be more readily discerned, both as to the markings of the signal and as to the movements thereof, than is possible with a bunting flag. The device is not affected by air currents while in use, thus permitting effective, clear-cut signals to be sent there- 100 with.

Since the device when not used is collapsed in a manner to protect the greater part of the surface thereof, the likelihood of the surface becoming soiled is reduced to a 105 minimum. Furthermore, fraying or tearing of the signaling device is impossible, thus increasing the life of the device by reason of this increased durability. The surface may also be readily cleaned, if soiled. 110

By reason of the exposure of the full area of the device at all times, irrespective of the air currents, the importance of a suitable background is reduced to a minimum. Furthermore, a signal made in accordance with 115 my invention may be conveniently used by the occupants of captive or dirigible balloons, or upon shipboard.

It also may be made in smaller sizes, so as to be effectively used in practice work. 120

It is not my intention to limit my invention to the precise details of construction shown in the accompanying drawings, it being apparent that such may be varied without departing from the spirit and scope of 125 the invention.

Having described the invention what I claim as new, and desire to have protected by Letters Patent, is:—

1. A signaling device embodying therein 130

a sequence of rigid panels, means whereby said panels may be folded upon each other to permit the collapsing of the signal in its entirety, stay strips pivotally connected with 5 one of said panels and adapted to engage all of said panels when they are extended, and means holding said stay strips against movement when the device is extended, said panels being so colored as to present a well 10 defined design thereon when extended.

2. A signaling device embodying therein a staff, a sequence of rigid panels arranged in two groups upon opposite sides of said staff, a panel of each of said groups being 15 pivotally mounted upon said staff, means whereby the panels of each group may be folded upon each other to permit the collapsing of the signal in its entirety, and means whereby said panels are held against 20 movement when the device is extended, said panels being so colored as to present a well defined design thereon when extended.

3. A signaling device embodying therein a staff, a sequence of rigid panels arranged 25 in two groups upon opposite sides of said staff, a panel of each of said groups being pivotally mounted upon said staff, means whereby the panels of each group may be folded upon each other to permit the collapsing of the signal in its entirety, two stay 30 strips pivotally connected with a panel, said strips being arranged at opposite ends of the signal, and being adapted to engage all of the panels to hold them against movement 35 when the device is extended, and sockets carried by said staff adapted to receive said stay strips respectively, said panels being so colored as to present a well defined design thereon when extended.

40 4. A signaling device embodying therein a staff, a sequence of rigid panels arranged in two groups upon opposite sides of said staff, a panel of each of said groups being pivotally mounted upon said staff, means 45 whereby the panels of each group may be

folded upon each other to permit the collapsing of the signal in its entirety, the end panel of each group having a flange forming a pocket along the edge thereof, a stay strip pivotally mounted upon the end panels 50 of each group respectively, so as to fold within said pocket when the device is collapsed, the stay strip of each group being of a length to enter the pocket of the other group when said panels are extended, and 55 means holding said stay strips in relation to said staff, said panels being so colored as to present a well defined design thereon when extended.

5. A signaling device embodying therein 60 a staff, a sequence of rigid panels arranged in two groups upon opposite sides of said staff, a panel of each of said groups being pivotally mounted upon said staff, means whereby the panels of each group may be 65 folded upon each other to permit the collapsing of the signal in its entirety, the end panel of each group having a flange forming a pocket along the edge thereof, a stay strip pivotally mounted upon the end panels of 70 each group respectively, so as to fold within said pocket when the device is collapsed, said stay strip of each group being of a length to enter the pocket of the other group when said panels are extended, a hook pivotally mounted adjacent said pocket-forming flange of each group and adapted to engage the end panel of the other group, said 75 hooks being arranged at opposite ends of said panels, and means holding said stay strips in relation to said staff, said panels being so colored as to present a well defined 80 design thereon when extended.

In witness whereof I have hereunto affixed my signature, this 4th day of May, 1918, in 85 the presence of two subscribing witnesses.

CHARLES STANLEY JACOB.
